UNITED STATES PATENT OFFICE.

CHARLES T. LEMON, OF RIPLEY, OHIO.

LIGHTING SYSTEM FOR MOTOR-VEHICLES.

1,210,335.

Specification of Letters Patent. Patented Dec. 26, 1916.

Application filed January 12, 1916. Serial No. 71,746.

To all whom it may concern:

Be it known that I, CHARLES T. LEMON, a citizen of the United States, residing at Ripley, in the county of Brown and State 5 of Ohio, have invented new and useful Improvements in Lighting Systems for Motor-Vehicles, of which the following is a specification.

This invention relates to improvements in 10 circuit closers and has particular application to a circuit closing device for use in connection with the lighting systems of motor vehicles.

In carrying out the present invention, it 15 is my purpose to provide a circuit closer or switch which will be under the control of the gear shifting lever and operable therefrom upon movement of the gear shifting lever to reverse position, and which may be 20 employed to control lamps at the front and rear ends of the vehicle so that the vicinity in the rear of the vehicle may be illuminated to facilitate backing.

With the above and other objects in view, 25 the invention consists in the construction, combination and arrangement of parts hereinafter set forth in and falling within the scope of the claim.

In the accompanying drawings, Figure 1 30 is an enlarged sectional view through the gear shifting lever switch. Fig. 2 is a similar view taken at right angles to Fig. 1. Fig. 3 is a top plan view showing the position of the switch upon the slotted segment 35 of the gear shifting lever.

17 designates the gear shifting lever working within an H-slot 18 formed in a segmental plate 19 and mounted upon the plate 19 adjacent to the "reverse" portion of the 40 H-slot 18 is a switch comprising a casing 20 preferably, although not necessarily, formed of insulating material. Arranged within the casing 20 adjacent to the upper end thereof is a transverse shaft 21 having one 45 end thereof projecting through the side wall of the casing adjacent to the slot 18 and fixed upon the shaft 21 and disposed within the casing 20 is a switch arm, 22, while mounted within the casing 21 adjacent to 50 the ends of the path of movement of the arm 22 are contact segments 23 and 24 respectively. Secured to the projecting end of the

shaft 21 is a Y-shaped arm 25 adapted to be engaged by a pin 26 secured to the gear shifting lever 17 when such lever is moved 55 to reversing position. Normally, the switch arm 22 is in engagement with the contact 23 and the Y-shaped arm 25 in a position to be engaged by the pin 26 when the lever 17 is moved to reversing position. Upon the 60 movement of the lever 17 to reversing position, the pin enters the space between the limbs of the Y-shaped arm and swings such arm from the full line position in Fig. 1 to the dotted line position, thereby rotating 65 the shaft 21 and swinging the switch arm 22 out of engagement with the contact 23 and into engagement with the contact 24. When the lever 17 is moved out of reversing position, the parts of the switch are restored to 70 normal position.

While I have herein shown and described the preferred form of my invention by way of illustration, I wish it to be understood that I do not limit or confine myself to the 75 precise details of construction herein described and delineated, as modification and variation may be made within the scope of the claim without departing from the spirit or the invention.

I claim:

The combination with the reversing lever of a motor vehicle, of a circuit closer comprising a casing, a horizontal shaft journaled in said casing and having one end 85 projecting through the casing, a switch arm secured to said shaft and depending therefrom within the casing and capable of swinging movement, contact segments disposed at the ends of the path of movement 90 of the switch arm and adapted to be engaged thereby, a Y-shaped arm fixed to the outer end of said shaft, and a pin on said reversing lever adapted to enter said Y-shaped arm in the movement of the reversing 95 lever to reversing position to swing said Y-shaped arm, said shaft and said switch arm.

In testimony whereof I affix my signature in presence of two witnesses.

CHARLES T. LEMON.
